UNITED STATES PATENT OFFICE.

JULIUS F. MEDVECZKY, OF SAN FRANCISCO, CALIFORNIA.

LIVE-MOTION ADVERTISING DEVICE.

1,095,410.

Specification of Letters Patent.

Patented May 5, 1914.

Application filed February 10, 1913. Serial No. 747,428.

To all whom it may concern:

Be it known that I, JULIUS F. MEDVECZKY, a subject of the King of Hungary, residing in the city and county of San Francisco and State of California, have invented new and useful Improvements in Live-Motion Advertising Devices, of which the following is a specification.

This invention relates to a device for producing life-like motion on signs and the like.

It is the object of this invention to provide a mechanical means for imitating the motion of effervescing liquids and other moving objects, which is simple in construction and operation, economical in manufacture, and compact.

The invention primarily resides in a plate having a peculiar design on its face and means for reciprocating the plate across an opening in a field whereby the design on the plate will cause the appearance or representation of effervescing liquids.

The invention further consists of the parts and the construction and combination of parts as hereinafter more fully described and claimed, having reference to the accompanying drawings, in which—

Figure 1 is a front elevation of a sign constructed in accordance with this invention. Fig. 2 is a similar view showing the face-plate of the sign removed. Fig. 3 is a vertical section on the line A—A of Fig. 1. Fig. 4 is a detail showing a modified form of the means for reciprocating the movable plate employed in this invention. Fig. 5 is a detail illustrating a modified form of the plate vibrating mechanism.

In the drawings 2 represents the face-plate or field of a sign, in which is formed an opening 3 conforming in general outline to the shape of a glass filled with a foaming liquid. The opening 3 may be covered with a transparent plate 4, as shown in Fig. 3, if desired.

Disposed rearward of the opening 3 in the face-plate 2 is a translucent plate 5, the color of which corresponds with the color of the liquid intended to be represented as contained in the glass represented by the opening 3.

Extending between the plate 5 and the opening 3 is a movable plate 6, which plate is designed to be reciprocated to intermittently expose a design or field on the face of the plate through the opening 3. The design on the face of the plate 6 is here

shown as consisting of a field *a* on the upper portion of the plate, which corresponds in color to the background of the face-plate 2 adjacent the upper portion of the opening 3 therein, a field *b* on the lower end of the plate 6 formed of radiating stripes of contrasted colors, and an intermediate field *c* of a color corresponding to that of the foam of the liquid represented. The plate 6 may be reciprocated in any desired manner. The means shown in Fig. 2 for accomplishing this action consists of a disk or wheel 7 connected to the plate 6 by means of a rod 8, which is pivotally attached to a wrist-pin 9 on the disk 7. The disk 7 may be rotated from any suitable source of power to impart the reciprocal movement to the plate 6, the means here shown consisting of a motor 10, which operates a driving belt 11 passing around the disk or wheel 7. It is obvious that any suitable means may be employed for rotating the disk 7.

Fig. 4 shows a means for reciprocating the plate 6 by fluid pressure, and comprises a piston 12 mounted in a cylinder 13, having a piston rod 14 pivotally connected with the upper end of the plate 6. The piston 12 is designed to be reciprocated within the cylinder 13 by means of a fluid pressure, such as air, steam, or water, which is admitted to the interior of the cylinder alternately above and below the piston 12, and exhausted therefrom by means of a valve 15 in the manner common in devices of this character.

The plate 6 is designed to have a length of travel or stroke which would be sufficient when the plate is in its uppermost position to obscure the field *a* behind the face-plate 2 and expose the field *c* through the upper portion of the opening 3, and when the plate 6 is in its lowermost position the field *a* will be exposed across the upper portion of the opening 3.

By reciprocating the plate 6 to cause the fields *a*—*b* and *c* thereon to have a vertical movement across the opening 3, the representation of the liquid in the glass will have the appearance of foaming, with the foam alternately rising and falling above the upper line of the represented glass. Means are provided for rapidly oscillating the plate 6 during its vertical reciprocal movement, which means are shown in Fig. 2 as consisting of a zigzag slot 16, in which a roller 17, carried by a bracket 18 on the plate 6, is adapted to ride. The slot 16 acts when the

plate 6 moves in a rotary direction to direct the roller 17 as it is carried up or down with the plate, first one way and then another, to impart an oscillating or vibrating movement to the plate. This oscillation of the plate 6 may also be accomplished by means of an eccentric 19 on a shaft 20, rotated from any suitable source of power; which eccentric 19 is connected to the plate 6 through a strap 21 and a connecting arm 22, as shown in Fig. 5. By rotating the eccentric 19, the plate 6 will be caused to oscillate on its pivot connection with its reciprocating means.

15 For the purpose of blending the radiating stripes 6 on the field 6 into the translucent background formed by the plate 5, the lower end of the plate 6 is rounded and is formed with a series of serrations 23. By thus 20 forming the lower end of the plate 6 and imparting a rapid oscillating or vibratory movement simultaneous with its vertical movement, the appearance of effervescence is obtained.

25 If desired, the plate 6 may be doubled to extend on opposite sides of the translucent plate 5, as shown in Fig. 3, and an opening 3' opposite the opening 3 formed in a face-plate 2' on the rear of the sign. By this 30 construction and arrangement the sign may be viewed on each side.

By providing a plate 6, adapted to be reciprocated with relation to the opening 3, a sign having a comparatively long and narrow opening 3 therein with a moving field therebehind may be made.

While I have shown the device as applied for the purpose of representing effervescing and foaming liquids, it is manifest that it is 40 equally applicable to illustrating other moving liquids or gases by forming the opening 3 to suit, and placing such design on the reciprocal plate 6 as may be required. For instance, the smoking of a cigar, or flash of a 45 gun, blowing of a whistle, and many other actions may be represented by the use of the mechanism herein set forth.

Having thus described my invention, what I claim and desire to secure by Letters Patent is:

1. In a sign, the combination of a reciprocal plate, a sign surface in front of the plate having an opening exposing the plate; said plate bearing a design comprising a trans-

verse field corresponding in color to that of 55 the background of the sign surface, a transverse field of radiating stripes of contrasting colors at the lower end of the plate and a field between the aforesaid fields contrasting in color thereto; and means for oscillating 60 the plate.

2. In a sign, a face-plate having an opening, a reciprocal plate behind said opening and adjacent the face-plate, said reciprocal plate having a design on its face comprising 65 adjacent fields of contrasting colors extending transversely of the plate, and a third field of radiating stripes; and means for reciprocating the plate longitudinally to move the fields in relation to the opening in the 70 face-plate.

3. In a sign, a face-plate having an opening, a reciprocal plate behind said opening and adjacent the face-plate, said reciprocal plate having a design on its face comprising 75 adjacent fields of contrasting colors extending transversely of the plate, and a third field of radiating stripes; means for reciprocating the plate longitudinally to move the fields in relation to the opening in the 80 face-plate, and means for vibrating the plate transversely.

4. In a sign, a face-plate having an opening, a reciprocal plate having a serrated end, and a design on the reciprocal plate comprising adjacent fields of contrasting colors, and a field of radiating stripes adjacent its serrated end; and means for giving the plate 85 an oscillating movement to move the fields in relation to the opening in the face-plate. 90

5. In a sign, a face-plate having an opening, a reciprocal plate having a serrated end, and a design on the reciprocal plate comprising adjacent fields of contrasting colors, and a field of radiating stripes adjacent its serrated end; means for giving the plate 95 an oscillating movement to cause the fields to move in relation to the opening in the face-plate, and a translucent plate adjacent the reciprocal plate extending across the 100 opening in the face-plate.

In testimony whereof I have hereunto set my hand in the presence of two subscribing witnesses.

JULIUS F. MEDVECZKY.
